CLAIM

The ornamental design for a champagne flute, as shown and described.

DESCRIPTION

FIG. 1 is a front side elevational view of a champagne flute showing our new design, the rear side and right and left sides being identical in appearance therewith.

FIG. 2 is a top plan view thereof; and

FIG. 3 is a bottom plan view thereof.

The stippled shading on the stem of our new design for a champagne flute represents a texture contrast.

FIG. 2

FIG. 3
